UNITED STATES PATENT OFFICE.

JAMES E. GROSJEAN, OF LIMA, OHIO.

SOLE FOR BOOTS AND SHOES.

Application filed September 13, 1923. Serial No. 662,477.

To all whom it may concern:

Be it known that I, JAMES E. GROSJEAN, a citizen of the United States, residing at Lima, in the county of Allen and State of Ohio, have invented new and useful Improvements in Soles for Boots and Shoes, of which the following is a specification.

The present invention relates to improvements in soles for boots and shoes and more particularly to soles of the class which utilize the wear-resisting properties of textile or similar fibrous material to provide a tough and durable wear surface.

The primary object of the invention is to provide a sole of this class which can be produced economically and which possesses great strength, and it also utilizes the wear-resisting properties of threads or cords which are presented endwise to the tread or wear surface, the present invention enabling these results to be attained inexpensively, as it is not necessary that the threads or cords be in the form of a woven or other definitely formed fabric structure, and hence materials which are usually discarded as waste by automobile tire manufacturers, and other discarded materials can be used in the manufacture of the improved soles.

To these and other ends, the invention consists in certain improvements and combinations and arrangements of parts, all as will be hereinafter more fully described, the features of novelty being pointed out particularly in the claims at the end of the specification.

In the accompanying drawings:

Figure 1 is a bottom plan view of the forward portion of a sole constructed in accordance with one embodiment of the invention;

Figure 2 represents a longitudinal section through the forward portion of a sole, as shown in Figure 1, during its course of manufacture and Figure 3 is a view similar to Figure 2 showing the forward portion of the sole when finished.

The present invention is applicable to soles and half soles suitable for use generally on boots and shoes where the qualities or properties of a rubber sole are desirable, the textile fiber constituent, according to the present invention, greatly increasing the strength and durability of the sole at relatively low cost. The preferred embodiment of the invention is illustrated in the accompanying drawings and will be here-

inafter described in detail, but it is to be understood that the invention is not restricted to the precise embodiment shown, as equivalent structures are contemplated and these will be included within the scope of the claims.

In the embodiment of the invention shown in Figures 1, 2 and 3, the sole comprises a body 1 which comprises preferably a rubber compound, such as that usually used in the making of rubber soles or heels, this portion of the sole preferably including a heel portion which may, if desired, be thicker than the remainder of the sole, the shank, and a margin 2 which surrounds the forward portion of the sole. The tread or wear surface designated 3, according to this embodiment of the invention, is composed of a rubber compound which may be similar to that generally used for the manufacture of rubber soles and heels, or it may be composed of any other material which will cure or is capable of vulcanization, it being advantageous to prepare this material in sheets from scraps of rubber compound which are discarded as waste in the manufacture of automobile tires, the tread or wear surface being stitched with cords or threads 4, thus providing textile threads which are distributed throughout the tread or wear surface and are presented endwise thereto, these threads possessing greater wear resisting properties over the rubber compound and thus materially increasing the durability of the sole.

In preparing the material to form the wear surface 3 it is preferable to roll out or otherwise prepare a flat sheet of the rubber compound and to apply a sheet of canvas 5, or other strong or tough material, preferably woven fabric, to one face of the sheet of rubber, this being done while the sheet of rubber compound is uncured, and the sheet of rubber compound and its accompanying canvas sheet or ply is then stitched with the threads 4, this being done preferably on a sewing machine, using either a coarse thread or cord, or a fine thread, or a thread of any desired thickness, and the stitches are preferably arranged in rows which may be spaced apart any desired distance, it being understood that by placing the rows of stitches closely together, the wear-resisting properties of the material are increased. Preferably the rows of stitches are arranged to cross one another, giving the material a substantially quilted effect. A

lock stitch is preferably used in order to effectively retain the threads or stitches in place during the wear of the sole.

The sheet of material comprising the superposed rubber compound and fabric 5 ply stitched substantially as above described, is in a form which enables the tread or wear surfaces to be readily and inexpensively cut in the desired form therefrom by dies. The blanks of material to form the wear surfaces of the soles are then inserted within the rubber margin or edge 2 of the soles and a layer or ply of tough material, preferably canvas or similar woven material 10 6 is preferably applied to one face of the structure, as shown in Figure 2. Also, it is preferable to provide a reinforcement between the shank of the sole and the adjacent edge of the tread or wear surface, the reinforcement 15 shown in the present instance comprising a strip of canvas or other tough woven material 7 having a ply of rubber 8 on one face thereof, this reinforcement being so applied that one end is interposed between the shank end of the tread or wear surface and the canvas or backing sheet 6, while its other end overlaps the shank portion 20 of the sole. The parts assembled as above described may then be placed in a mold and cured or vulcanized in the usual or well known way to give the sole its final or finished form and to securely unite its constituents. Figure 3 represents substantially the form of the finished sole, the rubber compound body 3 being vulcanized to the canvas backing 5 and to the surrounding rubber edge 3 of the sole, the canvas backing 5 and the surrounding margin or edge 2 of the sole being vulcanized to the 25 canvas or fabric ply 6 and the reinforcing strip 7 being embedded within the sole and securely vulcanized to the shank end of the tread surface 3, 5 and to the shank portion of the sole. The threads or cords comprising the stitching also become vulcanized within the rubber body 3 of the tread or wear surface, so that these threads will be securely held within the rubber body 3 while the sole undergoes wear.

Soles constructed as above described may be manufactured at less cost than those which employ plies of woven fabric or plies

of cord structure, the labor involved in their manufacture is reduced, and such soles possess greatly increased wear-resisting 55 properties and strength over soles composed of rubber compound only. By stitching the cords or threads through the rubber structure forming the tread or wear surface, a great number of threads become distributed throughout the wear surface, and, moreover, these threads are presented endwise to the wear surface of the sole so that the ends of the fibers composing the cords or threads resist wear most effectively. 60 Furthermore, the stitching prevents disintegration of the rubber body composing the wear surface, particularly in view of the fact that the stitched cords or threads become vulcanized within the rubber body 3. 65 70

I claim as my invention:—

1. A sole for boots and shoes comprising a tread composed of a layer of rubber having a thread stitched therethrough and exposed at the wear surface thereof, said 75 rubber layer and thread being vulcanized together.

2. A sole for boots and shoes comprising a tread composed of a body of rubber having lines of stitches extending across it and vulcanized therein and exposed at its wear surface.

3. A sole for boots and shoes comprising a tread composed of a body of rubber having intersecting rows of stitches of textile 85 thread extending across it and vulcanized therein and exposed at its wear surface.

4. A sole for boots and shoes comprising a tread composed of a body of vulcanizable material having intersecting rows of stitches 90 of textile thread extending across it, the thread being vulcanized therein and being presented endwise to the wear surface of the tread.

5. A sole for boots and shoes comprising 95 a layer of rubber, a layer of woven textile material superposed thereon, and textile thread stitched through said layers and exposed at the wear surface of the tread, the layers of rubber and textile material and the 100 thread being vulcanized.

In testimony whereof I have hereunto set my hand.

JAMES E. GROSJEAN.
